UNITED STATES PATENT OFFICE.

JAQUES EDWIN BRANDENBERGER, OF PARIS, FRANCE, ASSIGNOR TO LA SOCIETE LA CELLOPHANE, SIÈGE SOCIAL, OF PARIS, FRANCE.

PHOTOGRAPHIC FILM WITH A CARRIER PERMEABLE TO WATER.

Application filed March 7, 1921. Serial No. 450,399.

To all whom it may concern:

Be it known that I, JAQUES EDWIN BRANDENBERGER, citizen of the Republic of Switzerland and resident of Paris, France (post-office address 16 Rue du Louvre), have invented new and useful Photographic Films with Carriers Permeable to Water, which improvements are fully set forth in the following specification.

10 This invention relates to photographic films with a carrier that is permeable to water.

Photographic films with a carrier permeable to water have been obtained by soaking under certain definite conditions, the 15 permeable carriers, such as cellulose and other materials, in various baths with the object of forming the sensitive salt in the interior of the films. This salt therefore is found, as one can imagine, concentrated in 20 the vicinity of the two surfaces of the carrier, the concentration diminishing progressively towards the centre of the thickness of the carrier. From a photographic point of 25 view this double concentration of the sensitive salt on the surfaces may give rise to certain inconveniences such as insufficient definition of the image.

The object of the present invention is a 30 process which is applied to photographic films, with a carrier permeable to water, with the object of obtaining a single sensitive surface on the carrier; in other words to effect the concentration of the sensitive 35 salt on only one surface of the carrier.

To obtain this result, one of the following two processes may be used.

1. The permeable film, of whatever kind; 40 viscose for example, is thoroughly moistened beforehand, the surplus water being then pressed out. After this, the carrier being still wet, a photographic emulsion with a gelatine base is applied as a coating which is very uniformly distributed over the 45 surface of the film and remains so during all the time which precedes coagulation.

2. The permeable carriers are passed 50 through the first bath which serves to cause the film to swell up and impregnate it with one of the products intended to react subsequently. After this, and before passing the film through the second bath, it is doubled, that is to say, two films are laid one against the other, and passed for example between pressing rollers. Thus a

double film is obtained which is then submitted to the action of the final bath with the object of forming the sensitive salt in the interior of the film. After this operation the two films previously stuck together 60 are separated and thus two films are obtained in which the sensitive salt is found to be concentrated on a single surface.

The single figure of the accompanying drawing is a fragmental sectional view, on 65 a greatly enlarged scale, of a double film constructed as above described: 1—1 indicating the two permeable carriers or films, and 2—2 the layers or coatings of sensitive salt formed on their outer faces. 70

It is evident that instead of sticking the two films together between the first and second bath, they may be stuck together before or during their passage through the first bath. 75

This method of operating furnishes two films in every case; but evidently, at the expense of the output, each film could be fixed on a carrier, impervious to the baths, for example on a flat or cylindrical glass 80 surface and afterwards separated therefrom, thus obtaining the same result as that mentioned above.

What I claim and desire to secure by Letters Patent is:— 85

1. A method of manufacturing photographic films, comprising the steps of moistening a cellulosic carrier permeable to water with a liquid, expressing the surplus liquid from the carrier, and then subjecting one 90 surface only of the carrier to the action of a different liquid to form a sensitive layer on said surface; substantially as described.

2. A method of manufacturing photographic films comprising the steps of passing a cellulosic carrier permeable to water first through a solution of a salt which will cause the carrier to swell and become impregnated with the salt, and then through a solution of a salt which will react with the 95 first salt to produce a sensitive layer; doubling the carrier, so that two carriers are laid one against the other, prior to the passage of the carrier through the second solution, thereby to form the sensitive layer on solely 100 one surface of each carrier; and then separating the two carriers. 105

3. A method of manufacturing photographic films, comprising the steps of passing in a cellulosic carrier permeable to water 110

through a solution of a salt which will cause the carrier to swell and become impregnated with the salt; doubling the carrier, so that two carriers are laid one against the other, before the passage of the carrier through said solution has been completed; passing the doubled carrier through a solution of a salt which will react with the first salt to produce a sensitive layer on solely one surface of each carrier; and then separating the two carriers.

10 one surface of each carrier; and then separating the two carriers.

4. A method of manufacturing photographic films, comprising the steps of passing a cellulosic carrier permeable to water 15 through a solution of a salt which will cause the carrier to swell and become impregnat-

ed with the salt; doubling the carrier, so that two carriers are laid one against the other, during the passage of the carrier through said solution; passing the doubled carrier through a solution of a salt which will react with the first salt to produce a sensitive layer on solely one surface of each carrier; and then separating the two carriers. 20

In testimony whereof I have signed this specification in the presence of two subscribing witnesses.

JAQUES EDWIN BRANDENBERGER.
